UNITED STATES PATENT OFFICE

ALMON A. JOHNSON, OF SUPERIOR, WISCONSIN

STEERING MACHINE

Application filed July 13, 1928. Serial No. 292,512.

My invention relates to steering machines and has for its object the provision of a steering machine embodying means for automatically cushioning the helm in the event of an excessive blow against the rudder; means for automatically stopping or reversing the motor when said cushioning means is fully compressed, and means for automatically varying the speed of an electric follow-up controller 10 to conform to the speed variations of the helm in its path of travel. With these and other objects in view, it consists of the structures, combinations and arrangements of parts hereinafter described and claimed.

15 In the drawings, Fig. 1, is a diagrammatic view of a portion of a master controller and of a distant follow-up controller, omitting a relay system. Fig. 2, is a steering gear primarily controlled by said master controller. 20 Fig. 3, is a section, partly in elevation, on the line A—B of Fig. 2. Fig. 4, is a horizontal section on the line C—D of Fig. 3. Fig. 5, is an end elevation of the hereinafter described elliptical gears, showing in cross 25 section the shafts upon which they are respectively mounted.

In the drawings, 1 is a lead from any suitable source of electricity, not shown, to a master controller 2, from which the current 30 flows to a distant follow-up 3 and relay system, not shown, of any suitable construction adapted to govern the flow of any suitable power fluid to any suitable motor, or engine, as to an electric motor 4.

35 The master controller preferably embodies a manually operatable switch lever or circuit closer 2^a adapted to be moved into circuit closing contact with any one or other of any suitable number of contact points, as 2^b, 2^c, 2^d, which are connected by electrically parallel conductors with corresponding points 3^b, 3^c, 3^d, in the follow up. Said follow-up preferably embodies a motor-operated or engine-operated switch lever or circuit closer of any suitable form, as the ring 40 3^a adapted to contact with said points 3^b, 3^c, and 3^d, and additional points, if any, for similar purpose; which ring embodies two conducting segments insulated from each other 45 as by blocks 3^e and 3^f of insulating material.

One of said conducting segments is connected, as by the wire or brush 3^g with any suitable stationary conductor as with the concentric ring 3^h which is spaced or insulated from said ring 3^a. The other of said conducting segments is connected as by the wire or brush 3ⁱ with a different stationary conductor as with the concentric ring 3^j, which is spaced or insulated from the rings 3^a and 3^h. 55

From either one of said stationary rings, 60 as from the ring 3^h, a conductor, as 3^k, conducts the current to any suitable relay, not shown, adapted to govern the supply of a power fluid for operating said motor or engine ahead; and from the other of said stationary rings a conductor as the wire 3^l, conducts the current to any suitable relay, not shown, adapted to govern the supply of a power fluid for reversing said motor or engine. 65

70 One of said insulating blocks as 3^e is adapted to cut any of said points 3^b, 3^c, 3^d, or additional points, out of circuit when said block comes opposite to such point; and if such point should at the moment be in circuit with 75 said source and with either of said relays to admit power fluid to said motor or engine, said block will open the relay circuit, thereby effecting the discontinuance of the flow of power fluid to said motor or engine unless 80 the circuit through one of said relays be established through a different one of said points.

75 It will be observed that it is not the present purpose to claim, by this application, any invention in either said master controller, or follow up, or relay system per se, and that any suitable master controller, follow-up, or relay system heretofore known to the art, or otherwise, may be used by me in constructing my invention. 85

80 Said engine or motor is adapted to rotate a screw shaft, or worm 5 to which it is connected by any suitable transmission means, as by a train of gears, not shown, contained 90 in a gear case 5^a, which shaft engages a sleeve 6 mounted upon a crosshead 7 which is adapted to reciprocate upon a slide 8 preferably extending transversely of the vessel upon 95 which said steering gear is operated. 100

Said crosshead has mounted therein a journal block 9 extending vertically at right angles to said shaft and preferably offset from the vertical plane thereof, which block is normally centered between any suitable number of stiff cushion springs, as 10, 11, extending parallel to said shaft.

said sleeve is approximately at either end of its path in opposition to said centering means, and transmission means between said worm and said follow-up adapted to vary the speed of the follow-up to conform to the variable turning speed of the tiller.

3. The combination of an electric master controller, an electric follow-up controller, a worm, a prime mover governed by said follow-up, transmission means adapted to be driven by said prime mover and to drive said worm, a traveler engaged by said worm and adapted to be reciprocated thereby, a tiller sleeve pivotally mounted upon said traveler and adapted to reciprocate thereon parallel with said worm and independently thereof, yielding means for centering said sleeve between the ends of its path on said traveler, and means for automatically de-energizing the immediately prior active relay magnet of the follow-up while said sleeve is approximately at either end of its path in opposition to said centering means.

4. The combination of a master controller, a follow-up controller, a worm, a prime mover, transmission means adapted to be driven by said prime mover and to drive said worm, a traveler engaged by said worm and adapted to be reciprocated thereby, a tiller sleeve pivotally mounted upon said traveler and offset transversely from said worm and means for driving said follow-up at a variable speed conforming to the varying turning speed of the tiller.

35 5. The combination of a reciprocable traveler, means for reciprocating said traveler, a lever, a sleeve adapted to slide on said lever, said sleeve being pivotally mounted on said traveler and adapted to reciprocate thereon under an excessive lateral impulse by said lever, and yielding means for cushioning said sleeve between the ends of its path of reciprocation on said traveler in the absence of such impulse, said lever being adapted to 40 extend at various angles to said yielding means depending upon the varied positions of said traveler in its own line of travel.

6. The combination of a reciprocable traveler, means for reciprocating said traveler, a rudder tiller extending at an angle to the path of said traveler, a sleeve adapted to slide on said tiller, said sleeve being pivotally and reciprocatably mounted upon said traveler and adapted to reciprocate thereon independently of the movement of said traveler but in a path approximately parallel to the path of said traveler, and yielding means for cushioning said sleeve between the ends of its independent path, said tiller being adapted to extend at various angles to said cushioning means.

7. The combination of an electric master controller, an electric follow-up controller, an electric motor governed by said follow-up, a worm driven by said motor, a traveler

driven by said worm, a tiller extending at an angle to said worm, a sleeve adapted to slide on said tiller, said sleeve being pivotally mounted on said traveler and further adapted to reciprocate thereon approximately parallel with said worm and independently of the movement of said traveler, yielding means positioned on said traveler for normally centering said sleeve between the ends of its path of reciprocation upon said traveler, electric reversing switches in the circuit of the follow-up, a corresponding one of said switches being adapted to be operated by said sleeve to reverse said motor when said sleeve is approximately at either end of its path of independent reciprocation on said traveler, and resilient means for automatically returning said operated switch to its normal position and circuit when said sleeve retreats from the corresponding end of its said independent path of reciprocation.

8. The combination of a reciprocable traveler, means for reciprocating said traveler in a straight path, a lever, a sleeve adapted to slide on said lever, said sleeve being movably mounted on said traveler and adapted to reciprocate thereon under an excessive lateral impulse by said lever, and yielding means for cushioning said sleeve intermediate of the ends of its path of reciprocation on said traveler.

9. The combination of a traveler, means for reciprocating said traveler, a lever, a sleeve adapted to slide on said lever, said sleeve being movably mounted on said traveler and adapted to reciprocate thereon under an abnormal lateral impulse by said lever, and means for automatically reversing the movement of the means for reciprocating said traveler when said sleeve is approximately at either end of its path of travel on said traveler.

10. The combination of a traveler, means for reciprocating said traveler, a lever, a sleeve adapted to slide on said lever, said sleeve being movably mounted on said traveler and adapted to reciprocate thereon under an abnormal lateral impulse by said lever, and means for automatically reversing the movement of the means for reciprocating said traveler when said sleeve is approximately at either end of its path of reciprocation on said traveler and for reinstating the previous movement of the means for reciprocating said traveler when said sleeve has retreated from reversing position near an end of said path.

11. The combination of a reciprocable traveler, means for reciprocating said traveler including a source of electricity, an electric motor in circuit with said source and mechanical devices for transmitting power from said motor to said traveler, a lever, a sleeve adapted to slide on said lever, said sleeve being mounted on said traveler and

adapted to reciprocate thereon under an abnormal lateral impulse by said lever, and an electric reversing switch for reversing the direction of the current through said motor when said sleeve is at an end of its path of reciprocation on said traveler, said switch being adapted to be moved to reversing position by said sleeve.

In testimony whereof, I hereunto affix my
10 signature.

ALMON A. JOHNSON.
